DESIGN FOR A MEDALLION OR THE LIKE

Samuel Meisel, New York, N. Y.

Application November 19, 1938, Serial No. 81,240

Term of patent 3½ years

To all whom it may concern:

Be it known that Samuel Meisel, a citizen of the United States and resident of New York city, in the county of New York and State of New York, has invented a new, original, and ornamental Design for a Medallion or the like, of which the following is a specification, reference being had to the accompanying drawing forming part thereof, in which,

Fig. 1 is a top plan view of a medallion or the like embodying my design;

Fig. 2 is a cross-sectional view thereof taken substantially on the line 2—2 of Fig. 1.

I claim:

The ornamental design for a medallion or the like, substantially as shown.

SAMUEL MEISEL.
